US0D1080950S

(12) **United States Design Patent** (10) **Patent No.:** **US D1,080,950 S**
(45) **Date of Patent:** **** Jun. 24, 2025**

(54) **WORKING LAMP**

(71) Applicant: **Xiamen PVTECH Co., Ltd.**, Fujian (CN)

(72) Inventors: **Sijia Wang**, Fujian (CN); **Liangliang Cao**, Fujian (CN); **Fuxing Lu**, Fujian (CN)

(73) Assignee: **Xiamen PVTECH Co., Ltd.**, Fujian (CN)

(**) Term: **15 Years**

(21) Appl. No.: **29/863,741**

(22) Filed: **Dec. 22, 2022**

(30) **Foreign Application Priority Data**

Oct. 13, 2022 (CN) 202230675232.2

(51) **LOC (15) Cl.** **26-05**

(52) **U.S. Cl.**

USPC **D26/63; D26/72**

(57) **CLAIM**

The ornamental design for a working lamp as shown and described.

DESCRIPTION

FIG. 1 is a perspective view for a working lamp showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is an another perspective view for a working lamp showing our new design.

The showing of evenly broken lines is for illustrating portions of the article that form no part of the claimed design.

1 Claim, 8 Drawing Sheets
